US00D796532S

(12) **United States Design Patent** (10) **Patent No.:** **US D796,532 S**
Caldwell et al. (45) **Date of Patent:** **** Sep. 5, 2017**

(54) **DISPLAY SCREEN OR PORTION THEREOF WITH A GRAPHICAL USER INTERFACE**

(71) Applicant: **MX Technologies, Inc.**, Lehi, UT (US)

(72) Inventors: **John Ryan Caldwell**, Lehi, UT (US); **Ronald Brennan Knotts**, Provo, UT (US); **Jonathan R. Hopkins**, Pleasant Grove, UT (US)

(73) Assignee: **MX TECHNOLOGIES, INC.**, Lehi, UT (US)

(**) Term: **15 Years**

(21) Appl. No.: **29/556,877**

(22) Filed: **Mar. 3, 2016**

Related U.S. Application Data

(63) Continuation of application No. 29/543,025, filed on Oct. 20, 2015, now Pat. No. Des. 752,083, and a continuation of application No. 14/481,772, filed on Sep. 9, 2014.

CLAIM

The ornamental design for a display screen or portion thereof with a graphical user interface, as shown and described.

DESCRIPTION

The FIGURE is a front view of a display screen or portion thereof with a graphical user interface.

The broken line showing of the display screen is provided for the purpose of illustrating portions of the article and forms no part of the claimed design.

1 Claim, 1 Drawing Sheet
